D15-75. OR D11,971 EX

No. 11,971

September 28, 1880

UNITED STATES PATENT OFFICE.

JACOB STEPHAN, OF CLEVELAND, OHIO.

DESIGN FOR A SEWING-MACHINE CASE.

SPECIFICATION forming part of Design No. 11,971, dated September 28, 1880.

Application filed June 18, 1880. Term of patent 7 years.

To all whom it may concern:

Be it known that I, JACOB STEPHAN, a citizen of the United States, residing at Cleveland, in the county of Cuyahoga, State of Ohio, have invented and produced a new and original Design for Sewing-Machine Cases, of which the following is a specification, reference being had to the accompanying drawing, forming a part thereof.

10 In the drawing is shown a view, in perspective, of a sewing-machine cover constructed according to my design.

In the said drawing, A represents the front of the cover, having a large recessed ornamented panel, A'. This panel may or may not be made of a different kind of wood from that in which the balance of the cover is constructed. This panel is provided with a central inclined portion, A², extending from one upper corner 15 to the opposite lower corner, wherein is inlaid with a different-colored wood (preferably with a wood of a lighter color) the name of the machine to which the case is attached.

B is one end of the case, which is ornamented 20 with a panel having a circular top.

C is the top, and D a corrugated curved piece connecting the top with the front.

What I claim is—

1. In a design for a sewing-machine case, the front A, having recessed panel A', provided with inclined portion A², the flat top C, and the longitudinally-corrugated portion D, formed in a vertically-curved plane between said top and front, substantially as set forth. 30

2. In a design for a sewing-machine case, 35 the front A, having recessed panel A', provided with central inclined portion, A², the flat top C, the corrugated portion D, extending in vertically-curved plane between said front and top, and the end B, provided with a 40 panel having a curved top, substantially as set forth.

In testimony whereof I have signed my name to this specification in the presence of two subscribing witnesses.

JACOB STEPHAN.
